UNITED STATES PATENT OFFICE.

HARRY FEDER, OF NEW YORK, N. Y.

DRESS-STAY BLANK.

SPECIFICATION forming part of Letters Patent No. 727,323, dated May 5, 1903.

Application filed October 4, 1901. Renewed October 9, 1902. Serial No. 126,631. (No model.)

To all whom it may concern:

Be it known that I, HARRY FEDER, a citizen of the United States, and a resident of the borough of Manhattan, in the city and State 5 of New York, have invented a new and useful Dress-Stay Blank, of which the following is a specification.

My invention relates to a dress-stay blank from which stays of the desired length may 10 be cut at pleasure. The object is to provide a stay of uniform resiliency and strength which will maintain its elasticity in varying temperatures and conditions of atmosphere and which may be supplied at a low cost.

15 A practical embodiment of my invention is represented in the accompanying drawings, in which—

Figure 1 is a view of a portion of a continuous sectional strip of horn which either alone 20 or in connection with adjacent strips forms the stay-blank. Fig. 2 is a similar view showing the sections bound together. Fig. 3 is a similar view showing the strip covered with paper. Fig. 4 shows two strips each covered 25 with paper and the two bound together by a paper covering, and Fig. 5 represents a portion of a completed stay-blank made of two pairs of the strips bound together by a paper covering wound thereon and further connect- 30 ed by a cloth casing stitched thereon.

The continuous strip of horn is formed of sections as long as the crude material will practically admit of, the drawings, Figs. 1 and 2, showing the meeting ends of two consecutive sections, (denoted by *a* and *b*.) The drawings represent the strip about twice the size in transverse section which I prefer to use in practice. The meeting ends of the sections are scarfed, as shown at *a'* *b'*, and over- 35 lapped and then permanently united by a thread *c*, wound around them. The scarfing and winding together of the ends of the sections are performed with great accuracy and rapidity by machines designed for the purpose. The sectional continuous strip thus 40 formed is completely wrapped with paper in the form of a strip *d*, wound thereon and held in position by a suitable gum, the object being to thoroughly protect the strip from the 45 action of the moisture in the atmosphere and as far as possible from temperature changes. This complete paper covering glued on the

strip also serves to protect the horn from perspiration when the stay is in use, and so materially prolong its life. 55

The continuous sectional strip completely incased in its paper wrapping may be covered with cloth, as in Fig. 5, and form a stay-blank from which stays may be cut of such a length as may be desired for use, or two of these horn 60 strips may each be completely wrapped with paper and the two then wrapped in another cover *e*, as shown in Fig. 4, and these two then provided with a cloth casing *f*, as in Fig. 5, or more than two of these strips may 65 be each wound separately and then wound together—as, for example, two pairs of strips, as shown in Fig. 5—and these two pairs incased in the cloth casing *f*, with lines of stitching *g* *g'* *g''* intermediate of the two pairs, and 70 on opposite sides of the pairs providing flaps or margins *f'* *f''* for attaching the stay to the waist or garment. The wire-like stay-blank thus formed of strips of substantially the same size and strength throughout will provide stays of uniform lateral resiliency in all directions, and where a plurality of these strips are united in a blank the united ends of the sections of one strip will fall opposite the body of an adjacent strip, so that no weakness will be noticeable at any one place. 75

The number of strips in the stay-blank may be one or more, and the lateral section of the strip may be greater or less than that indicated, as may be found desirable in practice. 85

What I claim is—

A dress-stay blank of wire-like form and of substantially equal lateral resiliency in all directions, composed of sections of horn arranged end to end and bound together with 90 their surfaces in the same plane and provided with a gummed paper covering tightly wrapped thereon to protect the sectional blank from the influences of the atmosphere, substantially as set forth. 95

In testimony that I claim the foregoing as my invention I have signed my name, in presence of two witnesses, this 11th day of September, 1901.

HARRY FEDER.
